C. L. GOODRUM,
TELEPHONE EXCHANGE SYSTEM.
APPLICATION FILED FEB. 10, 1917.

1,254,682.

Patented Jan. 29, 1918.

UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,254,682.

Specification of Letters Patent. Patented Jan. 29, 1918.

Application filed February 10, 1917. Serial No. 147,802.

To all whom it may concern:

Be it known that I, CHARLES L. GOODRUM, a citizen of the United States, residing at New York, in the county of New York and 5 State of New York, have invented certain new and useful Improvements in Telephone-Exchange Systems, of which the following is a full, clear, concise, and exact description.

10 This invention relates to machine switching telephone exchange systems with subscribers' control, and has for its object the provision for partial supervision in systems of this character.

15 In accordance with this invention, a means is associated with the connector, which, when the connector is set, establishes a latent signal for indicating the number of the called line. If the connector operations 20 do not proceed in the normal manner, an annunciator is displayed before the operator. The operator may then operate a manual switching device which causes the display of this latent signal, thus indicating to her 25 the number of the line upon which the connector has been set. The operation of the manual switching device may also serve to connect her head-set to the calling line, whereby she can communicate with the calling 30 party.

Referring to the drawing, the invention will be more readily understood from a detailed description of the operation.

Upon the removal of the receiver by the 35 calling party at substation A, a line finder diagrammatically indicated at 1, extends such line to the selector diagrammatically indicated at 2. The calling party then operates the sender S to set the selector in operative relation to the desired group of trunks 40 terminating in connectors, whereupon an idle one of these trunks is automatically seized in the well-known manner. Upon the extension of the calling line to the connector, the following circuit is closed: free pole to battery, relay 3, brush 4, terminal 5, substation A, terminal 6, brush 7, brush 8, terminal 9, conductor 10, relay 11 to ground. Relay 11, in operating, energizes slow relay 45 12 which, in attracting its left armature interposes a break in the circuit of the release magnet 13, and in attracting its right armature, connects the back contact of the stepping relay 11 to the rotary stepping magnet 50 14 of the connector.

The calling party now operates his sender S to transmit the tens digit of the wanted number. Upon each retraction of the armature of relay 11 an impulse is transmitted over the following circuit to magnet 14, 60 ground: armature and back contact of relay 11, right armature and front contact of relay 12, conductor 15, outer right armature and back contact of relay 16, connector side switch arm 17, magnet 14 to free pole of 65 battery. The magnet 14, responding to these impulses, steps the shaft 21 around so as to bring one of the sets of brushes 24, 45 into operative relation with the contacts 25, 46. Upon the first retraction of the armature of 70 relay 11, a slow relay 18 is energized. This relay, in attracting its inner right armature, energizes the escape magnet 19 of the side switch of the connector. When the sender reaches its normal position and maintains 75 stepping relay 11 energized, relay 18, after an interval, retracts its armature, thus de-energizing the escape magnet which passes the side switch to position 2. In this position vertical stepping magnet 20 is substi- 80 tuted in the stepping circuit for rotary magnet 14. The calling party now operates his sender S in transmitting the units digit of the called number. Upon each retraction of the armature of relay 11 an impulse is trans- 85 mitted to magnet 20 which drives the selected brushes 24 over the selected group. Upon the first retraction of the armature of relay 11, slow relay 18 is again energized and en- 90 ergizes the escape magnet 19, as before. In position 2 side-switch arm 23 connects test relay 16 to the connector brush 24. Assuming now that the called line is busy, battery potential will be found upon its test terminal, as will hereinafter appear. When, 95 therefore, the brush 24 reaches the terminal 25 of the selected line, and before the escape magnet 19 retracts its armature, but after relay 18 has retracted its armatures, the fol- 100 lowing circuit is closed for test relay 16: ground, inner armature and back contact of relay 18, armature and contact of relay 19, conductor 26, right winding of relay 16, con- 105 ductor 27, arm 23 and its second contact, conductor 49, brush 24, terminal 25 to free pole of battery. Relay 16 in attracting its left armature, locks itself over the following circuit: free pole of battery, left winding of relay 16, left armature and contact 28 there- 110 of, conductors 29, 30, left armature and 110

- front contact of relay 12 to ground. The attraction of this armature also closes a circuit for the escape magnet 19 to hold the same energized in order to prevent the side 5 switch from going into the ringing position: free pole of battery, magnet 19, arm 33 and its second contact, conductor 34, contacts 35, 28 of relay 16, conductors 29, 30, left armature and front contact of relay 12 to ground.
- 10 In attracting its outer right armature relay 16 disconnects the magnet 20 from the back contact of relay 11, thus preventing further impulses from being transmitted to this magnet, and in attracting its inner right 15 armature connects a source of busy tone current 68 to the upper talking conductor and thence to the calling line to indicate to the calling party that the desired line is busy. Upon the replacement of the receiver 20 by such party, relays 11 and 12 are de-energized, which results in the closure of a circuit for the release magnet 13 of the connector as follows: free pole of battery, magnet 13, primary off-normal contact PON, 25 right armature and contact of relay 31, conductor 32, left armature and back contact of relay 12 to ground.
- If the desired line had been idle no potential being found on the contact 25, the circuit traced for relay 16 would not have been completed, and the side switch would have advanced into the ringing position upon the de-energization of slow relay 18 at the end of the units impulses. Arm 23 in position 3 closes a circuit for relay 40 and the cut-off relay of the called line. The potential thus applied to multiples 25 causes this line to test busy to other connectors. Relay 40 closes the ringing circuit as follows: Pole 40 of ringing generator 37, ringing cut-off relay 38, conductor 39, armature and front contact of relay 40, conductors 41, 42, arm 43, conductor 44, brush 45, terminal 46, line conductor 47, through the signaling apparatus at substation B, line conductor 48, terminal 25, brush 24, conductor 9, arm 23 and its third contact through relay 40 to battery and ground. In position 3 arm 33 closes a circuit for the escape magnet 19 as follows:
- 45 Free pole of battery, magnet 19, arm 33 and its third contact, armature and back contact of relay 38, conductor 30, left armature and front contact of relay 12 to ground. Upon the removal of the receiver by the party at 50 substation B the relay 38 becomes energized, opening the circuit of magnet 19 which passes the side switch into position 4, in which position talking current is fed to the called line over the following circuit: free 55 pole of battery, magnet 40, arm 23 and its fourth contact, conductor 49, brush 24, multiple 25, line conductor 48, through the telephonic apparatus at substation B, conductor 47, multiple 46, brush 45, conductor 44, arm 43 and its fourth contact, conductors 50, 51,

relay 31 to ground. Upon the conclusion of the conversation and the replacement of the receivers the release circuit is closed as follows: free pole of battery, magnet 13, contact PON, right armature and back contact of relay 31, left armature and back contact of relay 12 to ground. 70

The connector brush shaft 21 carries, in addition to the regular brushes 24, 45, a brush 58 and a set of contacts 59 to be engaged thereby. This brush rotates with the shaft when it is being set by the rotary magnet 14. When, however, the shaft is elevated by the magnet 20, the shaft is free to move independently of the brush 58 by 75 reason of the key and slot construction shown. The shaft is also provided with a brush 60 which engages a set of terminals 61 during the upward movement of the shaft. This brush 60 is so mounted on the 80 shaft 21 that the shaft is free to rotate independently of the brush but carries the brush in its vertical movement. Connected to each contact of the group of contacts 61 is a lamp 62 and to each of the contacts of 85 the group of contacts 59 a lamp 63 is connected.

Thus, when the connector is set, the brushes 60 and 58 are in engagement with terminals of lamps corresponding to the 90 tens and units digits of the called line. In position 2 and in position 3 of the connector side switch a circuit for a relay 52 is closed as follows: free pole of battery, resistance 53, relay 52, arm 54 and its second 100 contact, contact 80 closed on the first rotary step of the connector shaft, to ground, or arm 54 and its third contact directly to ground. This relay is constructed so as not to attract its armature until after an interval of time longer than that which usually occurs between the first vertical step of the shaft 61 and the removal of the receiver by the called party, which results in the side switch passing out of the third or ringing 105 position and the opening of the circuit for relay 52 just traced. If, however, this interval of time is exceeded, the relay attracts its armature and lights the lamp 55. The operator then inserts plug 56 into jack 57. This 110 results in the illumination of one of the tens and one of the units lamps 62, 63, to indicate to the operator the number being called. The circuit for the lamp of group 62 is as 115 follows: free pole of battery, lamp 62, terminal 61, brush 60, conductor 64, contacts 65, 66 to ground. The circuit for the lamp of group 63 is as follows: free pole of battery, lamp 63, contact 59, brush 58, conductor 69, contacts 67, 65, 66 to ground. The 120 closure of contact 66 also shunts out the relay 52 which thereupon de-energizes, extinguishing lamp 55. The operator can now, by means of her head-set H, communicate 125 with the calling party. 130

The tens and units digits of the called line are indicated to the operator by the lighted lamps 63, 62, respectively. The hundreds digit would be indicated to her by the position the lamp 55 and its associated jack 57 occupy in the bank of similar lamps and jacks of the other connectors serving the thousand to which the called number belongs, and the thousands digit by the particular bank in which the lamp 55 is located.

The lamps 62, 63, however, may and in practice would be common to a number of connectors, the terminals 59 and 61 being multiplied at such connectors.

The lamp 55 will also be lighted if the calling party, upon receiving the busy signal, does not immediately replace his receiver. The operator may then communicate with the calling party and inform him that the line desired is busy.

What is claimed is:

1. In a telephone exchange system, the combination with telephone lines, means including connector switches for interconnecting said lines, means associated with said connectors for designating the line upon which a connector is set, said means being prepared for actuation upon the setting of the connector, and manual means for actuating said designating means.

2. In a telephone exchange system, the combination with telephone lines, means including connector switches for interconnecting said lines, a latent visual signal for indicating the called line established by the setting of the connector on such line, and manual means for displaying said indicating means.

3. In a telephone exchange system, the combination with telephone lines, means including connector switches for interconnecting said lines, a latent visual signal associated with said connectors for designating the line upon which a connector is set, said signal being established upon the setting of the connector, an annunciator for each connector, means for operating the same, an operator's telephone set, and manual means for connecting said set to the calling line and for displaying said signal.

4. In a telephone exchange system, the combination with telephone lines, means including connector switches for interconnecting said lines, banks of lamps for indicating

the tens and units digits of the called number, switching means associated with the connector for preparing circuits for a lamp of each group when said connector is set, and manual means for completing said circuits.

5. In a telephone exchange system, the combination with telephone lines, means including connector switches for interconnecting said lines, a source of signaling current, means for applying such source to the selected line, means associated with said connectors for designating the lines upon which a connector is set, said means being prepared for actuation upon the setting of the connector, an annunciator for each connector, a circuit for operating said annunciator, means for closing the same if said source is connected to the called line longer than a predetermined interval, and manual means for actuating said indicating means.

6. In a telephone exchange system, the combination with telephone lines, means including connector switches for interconnecting said lines, banks of lamps for indicating the tens and units digits of the called number, a pair of brushes mounted on the connector shaft for preparing circuits for a lamp of each group when said connector is set, and manual means associated with said connector for completing such circuits.

7. In a telephone exchange system, the combination with telephone lines, means including connector switches for interconnecting said lines, said connector switches having a rotary and a vertical movement, banks of lamps for indicating the tens and units digits of the called line, two groups of terminals on the connector for said lamp groups, a brush movable with the shaft during the rotary movement thereof to prepare a circuit for one of the lamps of the tens group, said brush being free to rotate with said shaft but being prevented from being elevated therewith, a second brush on said shaft for engagement with the terminals of the units group of lamps said brush partaking only of the vertical movement of the shaft and preparing a circuit for a units lamp when the connector is set, and manual means for completing said circuits.

In witness whereof, I hereunto subscribe my name this 9th day of February, A. D. 1917.

CHARLES L. GOODRUM
